UNITED STATES PATENT OFFICE.

CHARLES KNOX HARDING, OF CHICAGO, ILLINOIS.

NON-CARBONIZING SPARK-PLUG.

1,275,020.

Specification of Letters Patent. Patented Aug. 6, 1918.

Application filed July 19, 1916. Serial No. 110,027.

To all whom it may concern:

Be it known that I, CHARLES KNOX HARDING, a citizen of the United States, residing at Chicago, in the county of Cook and State 5 of Illinois, have invented a certain new and useful Improvement in Non-Carbonizing Spark-Plugs, of which the following is a specification.

My invention relates to spark plugs for 10 use in connection with internal combustion engines, and the object of the invention is to prevent the fouling of the parts with carbon. Viewed in its general aspects, my invention consists in using a catalytic material to produce flameless catalytic combustion of part of the explosive vapor and keep the parts, especially the insulator, free 15 from deposits of carbon. It will be understood that in addition to the disadvantage 20 arising when the sparking points of a spark plug become coated with carbon, there is another serious cause of trouble in spark plugs, to-wit: the deposition of carbon on the insulator, resulting in a short circuiting 25 of the electrodes. The purpose of my invention is to prevent the deposition of solid carbon, especially on the insulator.

One form of structure for carrying out 30 the invention is illustrated in the accompanying drawings, in which:

Figure 1 is a view of the device chiefly in longitudinal section, and

Fig. 2 is a perspective of the catalytic cylinder which forms one of the elements of 35 the device.

Similar numerals refer to similar parts in the two views.

The shell or body 1 of the plug is provided with external screw threads 2 near 40 the bottom for screwing into the engine cylinder. This shell is made of metal, usually iron or steel and, being screwed into the end of the cylinder, is thereby electrically "grounded". The insulator 3 consists 45 of porcelain or other suitable material and is held in place in the shell by a nut or bushing 4. As usual, the insulator is longitudinally apertured to receive the electrode rod 5. In the present instance the rod is externally threaded from top to bottom, and 50 at the top is provided with a suitable nut 6 for binding the electric conductor (not shown) and holding it in electrical contact with the electrode rod. At the lower end 55 of the electrode rod is a sparking point 8 which co-operates with a sparking point 9,

which is in electrical contact with the shell and is supported thereby.

In so far as the parts have been thus far described, they may assume any standard 60 or suitable form without exceeding the scope of the invention. I will now describe the characteristics which are more intimately associated with the principle of the invention:

An annular chamber 10 is formed in the lower end of the insulator, the diameter of this chamber being considerably larger than the diameter of the electrode rod. Into this chamber I introduce a hollow cylinder 11 having catalytic properties. The internal diameter of the cylinder is large enough to accommodate the rod and the external diameter is small enough to leave a cylindrical space between it and the internal wall of the 75 insulator. This cylinder is held in place by any suitable means, the present holding means comprising a nut 12 which screws on to the rod and engages the upper end of the cylinder, and the nut 13 which screws on to 80 the rod and engages the lower end of the cylinder. By preference, nut 13 has an external diameter smaller than the external diameter of the catalytic cylinder and is partially counter sunk into the end of the 85 said cylinder.

The catalytic body 11 may be composed of or treated with any suitable catalytic material which will produce flameless catalytic combustion, such, for example, as are described in my U. S. Patent No. 803,534, October 31, 1905, and No. 1,067,983, July 22, 1913. By preference, the catalytic structure 90 is composed principally of the oxides of the radio active elements thorium and uranium 95 as described in my later U. S. patent above mentioned. It will be understood that catalytic combustion may take place at a much lower temperature, (to-wit: 460 degrees Fahrenheit, more or less) than the temperature 100 at which flaming combustion or explosion can take place.

In operation, when the device is in place in the engine and the electrode rod 5 is electrically energized, an electric spark will 105 jump across the gap between the sparking points, 8, 9 in accordance with the timing of the timing device of the engine. After the engine has been operating long enough for the engine cylinder to become well 110 heated, the lower end of the insulator 3 will become heated, as will also the catalytic

cylinder 11. During the compression stroke which precedes the explosion, and which precedes the jumping of the spark from one of the sparking points to the other, the explosive gaseous mixture will be forced up into the chamber 10 surrounding the cylinder 11. As these parts are hot, albeit at a temperature considerably below the temperature at which a flame will be kindled in the gas, catalytic combustion of part of the gaseous mixture will take place in and adjacent to said body. This combustion is a true and rapid oxidizing action but it occurs without raising the temperature to a point where the explosive mixture will be kindled into a flame as it is characteristic of combustion produced by contact processes with solid catalytic agents in gaseous combustible mixtures to be localized and not to propagate through the whole of the mixture.

According to my present understanding, the resulting benefit is at least two-fold. In the first place, as catalytic combustion is a true oxidizing action there will be less oxidizing remaining to be done to that small portion of the explosive fuel-air mixture in the chamber 10 in contact with the insulator and catalytic body when the explosion occurs, and hence, as a result of this pre-oxidizing, the total period of oxidation will be increased with a consequent opportunity for the oxidation to be more complete by this double combustion produced by supplementing the ordinary combustion by preliminary flameless catalytic combustion and promoting complete and clean burning of that part of the charge which would tend otherwise to deposit carbon on the insulator. This is especially important where present day commercial gasoline is employed from which to obtain the explosive mixture. Such gasoline usually contains a certain percentage of oil having a relatively high boiling point, and in this the carbon aggregates occur in such form that the carbon cannot be completely oxidized in the short period of time afforded by the explosion or flaming combustion in the engine cylinder to entirely prevent the deposit of some small part of unburned carbon upon interior surfaces of the engine. In the second place, the parts of the insulator will be kept too hot for the deposition of carbon, or if carbon would be deposited it will promptly be burned off.

Thus in my device there will be prevented the deposition of carbon on the external surface of the lower end of the insulator where, if much carbon were deposited, there would be tendency for electric leakage across from the insulator to the adjacent part of the shell 2. As a result of my invention the parts will all be kept free from carbon, and hence, will be kept in proper operating condition.

Reference may be had to my United States

Patent No. 1,198,542 of September 19, 1916, for structure for producing flameless catalytic combustion which describes a specific form or variety of catalytic structure suitable for producing heat from gaseous combustible mixtures without igniting or inflaming the mixtures, but it will be understood as heretofore mentioned in the specification that for use in a non carbonizing spark plug any suitable or well-known catalytic agent or structure may be employed that will produce sufficient heat during the time prior to the explosion of the mixture, and when the explosive mixture always contains sufficient free and unburned oxygen to insure the burning off of carbon or carbon deposits from the hot insulator and which combustion does not inflame the mixture or interfere with the regular electric ignition which explodes the entire mixture for the production of power.

Having thus described my invention, what I claim as new and desire to secure by Letters Patent, is:

1. A non carbonizing spark plug having electric sparking points, an insulator and catalytic means for producing flameless combustion of part of the explosive mixture in the vicinity of the insulator.

2. A non carbonizing spark plug having electric sparking points, an insulator means for electrically exploding the whole mixture, and catalytic means for producing flameless catalytic combustion of part of the mixture to heat the insulator.

3. An electric non carbonizing spark plug having a shell, an insulator, means for electrically exploding the explosive mixture, and a catalytic body associated with said insulator for producing flameless catalytic combustion of part of the mixture and thereby heating the insulator prior to the explosion of the mixture when there is excess oxygen present to burn carbon off the insulator.

4. An electric non carbonizing spark plug for internal combustion engines, having a shell, sparking points, an insulator for insulating one of said points from the other, and a catalytic structure countersunk into and spaced apart from the internal wall of said insulator that will produce heat by oxidizing a portion of the explosive mixture by contact combustion without inflaming the mixture and thereby maintain a high temperature of the insulator at a time when there is always an abundance of free oxygen in the mixture to cause carbon to burn off the hot insulator before the mixture is fouled by the explosion produced by the electric spark.

5. A non carbonizing spark plug for internal combustion engines having a conductive shell, an insulator mounted therein and spaced apart therefrom, electrodes for elec-

trically exploding the explosive mixture, a catalytic body entering into a chamber in said insulator and means for passing some of the explosive mixture into contact with said catalytic body to be oxidized with flameless combustion and heat the insulator in the presence of free oxygen of the explosive mixture to burn off carbon from the insulator prior to the electric ignition of the mixture.

6. An electric non-carbonizing spark plug having means for electrically exploding the mixture, and a catalytic body for producing catalytic flameless combustion of some of the explosive and thereby heating the insulator and burning off carbon mixture prior to the electric ignition thereof, said catalytic body containing thorium oxid and a radio active element associated therewith.

7. In a non carbonizing spark plug, the combination of a conductive shell, an insulator mounted therein, said insulator having a chamber in the bottom, electrodes, and a cylinder extending into said chamber and spaced apart therefrom, said chamber communicating with the inside of the engine cyl-

inder and being thereby adapted to contact with a portion of part of the explosive mixture, said cylinder having radio active properties for producing flameless combustion of the explosive mixture thus heating the insulator and burning the carbon therefrom in the presence of oxygen of the unexploded mixture before the electric ignition explodes the whole charge for the production of power.

8. A spark plug comprising conducting electrodes, an insulator therebetween having interior surfaces forming part of a chamber for the reception of a portion of the combustible mixture, and catalytic means for producing flameless combustion of part of the mixture in said chamber.

9. In a spark plug, an insulator and catalytic means for maintaining the insulator at the oxidizing temperature of carbon, the catalytic means operating over a period of time appreciably longer than the period of inflammation of the combustible mixture.

In witness whereof, I have hereunto subscribed my name.

CHARLES KNOX HARDING.
